UNITED STATES PATENT OFFICE.

PETER HALL ALLISON, OF TORRINGTON, CONNECTICUT.

MOLD.

954,368.

Specification of Letters Patent.

Patented Apr. 5, 1910.

Application filed June 12, 1909. Serial No. 501,730.

To all whom it may concern:

Be it known that I, PETER HALL ALLISON, a subject of the King of Great Britain, and a resident of Torrington, in the county of 5 Litchfield and State of Connecticut, have invented a new and Improved Mold, of which the following is a full, clear, and exact description.

The invention relates to molds used for 10 casting ingots, such as brass bars, to be subsequently rolled into sheet or other form.

The object of the invention is to provide 15 a new and improved mold capable of being opened and closed without taking up much floor space, and arranged to prevent the formation of fins and to allow convenient and quick removal of the casting irrespective of any change in the members of the mold owing to expansion and contraction.

20 For the purpose mentioned, the mold is formed of two mold members, hinged together at one side, to allow of swinging the mold open in a lateral direction.

Figure 1 is a side elevation of the mold; 25 Fig. 2 is a transverse section of the same; and Fig. 3 is a sectional plan view of the same.

The rear and front mold members A and B are made approximately L-shape in 30 cross section, and the rear member A is provided with a forwardly projecting bottom A' forming the bottom of the mold. On one side of the mold members A and B are formed the hinge eyes C and D, engaged by 35 vertically disposed alined pintles E, to permit of swinging the front mold member B toward and from the rear mold member A on closing or opening the mold. The center of the hinge, formed by the lugs C and D 40 and the pintles E, is somewhat forward of the adjacent side of the rear mold member A, as plainly indicated in Fig. 3, so that the L-shaped mold member B can be readily swung into a closed position against the 45 mold member A, to close the mold at the front, rear, bottom and sides, while the top of the mold is left open for the reception of the molten metal, poured into the mold through a cut-out portion A² arranged on 50 the rear mold member A at the top thereof.

The joints F, F', F² between the mold members A and B, at the bottom and sides, are machined and interlocking, as will be readily understood by reference to Figs. 2 55 and 3, so that an exceedingly tight joint is provided, to prevent the formation of fins

when casting the ingot in the mold. Each of the joints F, F', F² is formed, by providing a right angled corner in one member, engaging a correspondingly-shaped rabbet 60 on the other member, as plainly indicated in Figs. 2 and 3.

By locating the axis or center of the hinge in the manner described, it will be readily seen, by reference to Fig. 3, that the mold member B can readily swing into closed or open position without danger of binding at the joints F, F' and F², at the same time insuring proper seating of the joint members to prevent leakage and the formation of 70 fins when pouring the molten metal into the mold. When doing this, the mold members are preferably locked in a closed position by suitable clamps G, as indicated in the drawings. After the casting is made the clamps 75 G are removed and the member B is swung open in a lateral direction, so that the casting can be readily dropped out of the rear member A of the mold.

It will be noticed that by making the 80 joints F, F', F² in the manner described, they are not affected by the expansion and contraction of the mold incident to the formation and removal of the ingot, so that the mold can be used over and over again with- 85 out danger of forming undesirable fins.

The under side of the rear mold member A projects a distance below the under side of the front mold member B, so that when the mold is resting on a suitable foundation, the 90 under side of the front member B is free of the support and can be readily swung into an open or a closed position.

It is understood that when the mold members A and B are closed and the molten 95 metal is poured into the mold, all the strain is taken up by the machined and the interlocked joints, thus relieving the hinge of undue strain.

Having thus described my invention, I 100 claim as new and desire to secure by Letters Patent:

1. A mold comprising two mold members hingedly connected with each other at one side, the members being approximately L- 105 shape in cross section, one of the members having an integral bottom, the said members having joints at the bottom and sides, the said joints each comprising a right-angled corner on one member engaging a corre- 110 spondingly shaped rabbet on the other member.

2. A mold comprising two mold members hingedly connected with each other at one side to allow one mold member to swing laterally toward or from the other member, 5 one of the members having an integral bottom forming the bottom of the mold, the said members having joints at the bottom and sides, the said joints each comprising a right angled corner on one member engaging a correspondingly shaped rabbet on the other member, the vertical axis of the hinge being forward of the adjacent joint of the members.
3. A mold, comprising a rear member, a 15 front member, and a hinge connecting the said members with each other at one side and a distance forward of the rear member, the said members being L-shape in cross section and the rear member having an integral 20 bottom and a cut out portion at the top.
4. A mold, comprising a rear member, a front member, and a hinge connecting the said members with each other at one side and a distance forward of the rear member, 25 the said members being L-shape in cross section and the rear member having an integral bottom and a cut out portion at the top, the joints of the said members being machined and interlocking.
- 30 5. A mold, comprising a rear member, a

front member, and a hinge connecting the said members with each other at one side and a distance forward of the rear member, the said members being L-shape in cross section and the rear member having an integral 35 bottom and a cut out portion at the top, the joints of the said members being machined and interlocking, and means for holding the free ends of the said members locked in closed position.

6. A mold comprising a rear member, a front member and hinges connecting the said members with each other at one side and at a point forward of the rear member, the said members being approximately L-shape in 45 cross section and the rear member having an integral forwardly projecting bottom forming the bottom of the mold, and a cut out portion at the top, the lower face of said rear member projecting below the lower face of 50 the front member, and clamps for holding the mold members in closed position.

In testimony whereof I have signed my name to this specification in the presence of two subscribing witnesses.

PETER HALL ALLISON.
